UNITED STATES PATENT OFFICE.

FREDERICK G. TEES, OF PHILADELPHIA, PENNSYLVANIA, ASSIGNOR OF ONE-HALF TO WILLIAM G. T. MARCELLUS, OF PHILADELPHIA, PENNSYLVANIA.

LUBRICATOR.

No. 844,211.

Specification of Letters Patent.

Patented Feb. 12, 1907.

Application filed November 21, 1905. Serial No. 288,342.

To all whom it may concern:

Be it known that I, FREDERICK G. TEES, a citizen of the United States, residing at Philadelphia, county of Philadelphia, and 5 State of Pennsylvania, have invented a certain new and useful Improvement in Lubricators, of which the following is a specification.

My invention relates to a new and useful 10 improvement in lubricators, and has for its object to provide an exceedingly simple and effective device by which either grease or oil may be fed to the bearings of machinery and so constructed that this feeding may be regulated; and a further object of my invention is 15 to provide for the operation of lubricators in multiple from one automatic actuating mechanism to put any or all of the lubricators in or out of action without arresting the operations of the automatic actuating mechanism 20 and to provide for feeding any or all of the lubricators by hand.

With these ends in view this invention consists in the details of construction and 25 combination of elements hereinafter set forth and then specifically designated by the claims.

In order that those skilled in the art to which this invention appertains may understand 30 how to make and use the same, the construction and operation will now be described in detail, referring to the accompanying drawings, forming a part of this specification, in which—

35 Figure 1 is an elevation of a set of my improved lubricators, the base to which they are attached being in section; Fig. 2, a vertical section of one of the lubricators; Fig. 3, a plan view of one of the lubricators, the plunger-rod being sectioned; Fig. 4, a section at the line $x x$ of Fig. 3; Fig. 5, a vertical section of the automatic actuating mechanism; Fig. 6, a plan view of the locking-ring by 40 which the cover of the lubricator is secured in place; Fig. 7, a similar view of the cover.

Referring to the drawings, A represents the body of any one of the lubricators, which is preferably of cylindrical shape, and B is a plunger fitted to slide vertically therein. This 45 plunger is rigidly secured to the lower end of the plunger-rod C and consists of two disks, between which is placed a compressible washer D, a nut E being run upon the reduced lower end of the plunger-rod, by means of which the washer may be compressed more or less, so as to increase its diameter,

thereby causing it to snugly fit the interior walls of the body A.

F represents the cover, which is provided with the plungers F', adapted to pass into 60 the cut-away portions G of the locking-ring H, which latter is threaded upon the upper end of the body A, so that when the cover is in place the turning of the locking-ring H will lock the cover in place, and as the 65 locking-ring is threaded upon the body the turning thereof will draw the cover tight upon its bearings.

I represents a nut fitted to revolve in the cover and held against displacement by the 70 yoke J, secured to the cover by suitable screws, and this nut projects upward above the surface of the cover and has fitted upon its projecting end a worm-gear K in such manner that said gear when not otherwise 75 locked to the nut may revolve freely around the hub thereof for the purpose set forth.

In order that the worm-gear may be locked to the nut so as to revolve therewith when occasion requires, a circular plug L is seated 80 in a recess formed in the gear and the periphery of this plug extends into a notch formed in the side of the projecting end of the nut, said notch being of the same curvature as the periphery of the plug. As will be seen, 85 when this plug is turned to the position shown in Fig. 3 it will lock the worm-gear to the nut, so that they will revolve together.

A notch L' is formed in the plug of a curvature which corresponds to the periphery of 90 the projecting end of the nut, so that when this plug is given a half-turn from the position shown in Fig. 3 the nut L' therein will coincide with the periphery of the projecting end of the nut, thus unlocking the worm-gear from the nut and permitting the former 95 to revolve without revolving the latter, and to facilitate the locking and unlocking of the worm-gear and nut a key-shank L² is formed with the plug upon which a key may be 100 placed to turn the latter.

The plunger-rod C is threaded throughout the greater portion of its length, so as to engage with the threads of the nut I, through which it passes, so that when this plunger-rod is held against rotation and the nut revolved said rod will be forced downward, thus forcing the plunger downward and feeding the grease or oil from the lubricator. 105

In order that the plunger-rod may be held against rotation while the nut is revolving, a latch M is pivoted to the body A, its inner

end being forked, so as to embrace the flattened sides of the plunger-rod, as clearly shown in Fig. 3, and on account of this latch being pivoted it may be swung backward out of engagement with the plunger-rod, thus leaving the latter free to revolve when occasion requires.

N is a bracket secured to the body of the lubricator and having secured therein the sleeve O, which latter has formed thereon the disk Q', and this sleeve serves as a bearing for the spindle P, which has secured upon its outer end the worm-wheel P', which meshes with the worm-gear K, so as to revolve the latter, and to the opposite end of the spindle P is secured the ratchet-wheel Q. Around this ratchet-wheel is a circular housing R, formed with the disk Q', and a portion of the circumference of said housing is cut away so as to expose a certain number of the teeth of the ratchet-wheel Q, for the purpose herein-after set forth.

A cam S is pivoted upon the spindle P and lies against the disk Q' within the housing R, a portion of the circumference of said cam coinciding with the outer periphery of the housing while the remaining portion of the circumference of said cam drops away to a point below the base of the teeth of the ratchet-wheel Q. This cam has a screw S' threaded therein, which projects through a slot in the disk Q' in order that the cam may be adjusted and when adjusted held in place by tightening up upon the screw.

T represents the actuating ratchet-wheel, which is fitted to revolve upon the housing R, and on the inside of the ratchet-wheel is pivoted a pawl T', forced inward by the spring T², as will be clearly seen by reference to Fig. 4. This pawl rides upon the outer periphery of the housing R until reaching the cut-away portion thereof, when it will be swung inward and come into engagement with the teeth of the ratchet Q as the ratchet

T is revolved. Now as a portion of the periphery of the cam S coincides with the periphery of the housing this pawl in its travel with the ratchet-wheel T will also ride upon the periphery of said cam, and as said cam is adjustable relative to the cut-away portion of the housing its adjustment will determine the number of teeth of the ratchet-wheel Q which will be exposed to the pawl T' during each revolution of the latter, for as long as the pawl is riding upon either the housing or its cam it cannot engage with the teeth of the ratchet-wheel Q, and therefore cannot actuate the same.

In order that the actuating ratchet-wheel T may be revolved step by step, a lever U is pivoted upon the housing R, so as to swing concentric therewith, and this lever carries a spring-actuated pawl V, set therein, said pawl engaging with the teeth of the actuating-ratchet, so that at every to-and-fro

movement of the lever this ratchet will be moved step by step, and the lever may be connected with any suitable mechanism for giving it this to-and-fro movement, or it may be weighted and utilized as a pendulum in order that it may swing to and fro when the lubricator is attached to a reciprocating part of a machine, such as a cross-head of an engine.

A cap U', having the body thereof threaded when in engagement with interior threads formed in the housing, holds the lever U in place.

From the foregoing description the operation of my improvement will be obviously as follows: The lever U being moved to and fro will, through the pawl V, revolve the ratchet T step by step, and in so doing carry the pawl T' around upon the housing and the cam S until it comes in engagement with the teeth of the ratchet-wheel Q, when it will move said ratchet-wheel in unison with the ratchet-wheel T until again riding out of engagement with the teeth of the ratchet-wheel Q, leaving the latter stationary, while the ratchet-wheel T continues to revolve. While the pawl T' is in engagement with the ratchet-wheel Q and the latter revolved thereby by the worm-wheel P' upon the same shaft with the ratchet-wheel Q will also be revolved and in turn revolve the worm-gear K. The revolving of this worm-gear will revolve the nut I when locked in engagement with the latter, and thereby feed the plunger-rod C and plunger-rod B downward, so as to effect the feeding of the lubricant to the bearings, and should it be desired to increase or decrease the amount of this feeding it may be readily accomplished by adjusting the cam S through the medium of the screw S', by which a greater or less number of teeth of the ratchet-wheel Q will be exposed to the action of the pawl T' during each revolution of the latter.

Should it become desirable to feed the lubricant by hand, it is only necessary to swing the latch M backward out of engagement with the plunger-rod, after which said rod may be turned by grasping the knob W and revolving the plunger-rod in the proper direction, when the plunger will be fed downward to any suitable extent.

For convenience in manipulating the locking-ring H a knob H' projects therefrom, so that the operator by grasping this knob may readily manipulate the locking-ring for removing the cover or locking the same in place.

In utilizing a multiple set of lubricators I arrange the caps or bodies A in series, as shown in Fig. 1, bolting them upon the base a by means of the nuts b run upon the nipples c, and each of these lubricators is so set relative to the one containing the actuating mechanism that the gear-wheels K mesh

with each other in order that when the first gear-wheel is operated by the actuating mechanism, as before described, its rotation will likewise rotate the gear-wheels of the remaining lubricators of the series, thus feeding the lubricant from each of these lubricators.

When it is desirable to throw out of action one or more of the lubricators, this is readily accomplished by turning the plug L so that the notch L' thereof registers with the periphery of the nut I, thereby unlocking the gear-wheel K from the nut, as before described, thus permitting the gear-wheel to revolve idly without effecting the feeding of the plunger-rod.

Where grease is to be used in the lubricator, the nipples c are connected with the bearing to be lubricated; but in case oil is used then a gooseneck d leads from the bottom of the lubricator, its upper end being connected with a glass tube e, so as to form a sight-feed or, if desired, the lower end of this gooseneck may be attached directly to the nipple c.

For certain purposes, such as automobiles, a series of feed-pipes f may lead from the bottom of the lubricator, so as to convey the lubricant to different bearings.

In order that the gear K may be revolved independent of the actuating mechanism, a key-hold g projects from the worm-wheel P', so that by the application of a key to this key-hold the worm-wheel may be revolved independent of the actuating mechanism, which in turn will revolve the gear K.

The body of the lubricator may be square or other angular shape which will hold the plunger against rotation, thereby doing away with the latch M.

Having thus fully described my invention, what I claim as new and useful is—

1. A lubricator consisting of a body forming a container for the lubricant, a plunger adapted to slide vertically within said body, a plunger-rod rigidly secured to the plunger, means for holding rod against rotation, a nut through which said rod is threaded, a worm-gear fitted to revolve around the nut,

means for locking or unlocking said gear to or from said nut and means for revolving the worm-gear, as specified.

2. In a lubricator of the character described, a plunger-rod, a plunger rigidly secured to the lower end of said rod, said plunger consisting of a compressible washer locked between two disks, a latch for embracing the flattened sides of said rod whereby the latter is prevented from revolving, a nut through which said nut is threaded, a cover in which said nut is fitted to revolve, a gear-wheel fitted to revolve upon the nut, a plug journaled in the gear-wheel, the periphery of said plug adapted to pass into a notch formed in the nut so as to lock the gear-wheel and nut together, said plug also having a notch formed therein for registering with the periphery of the nut whereby the latter will be unlocked leaving the gear free to revolve independent of the nut, and means for revolving the gear-wheel, for the purpose set forth.

3. The herein-described combination of a multiple lubricator consisting of a series of two or more containers, a plunger fitted to slide in each container, a plunger-rod rigidly secured to each of the plungers, a nut through which each of the plunger-rod is threaded, means for holding said plunger-rod against rotation when the nuts are revolved, a gear-wheel fitted to revolve around each of said nuts, the gear-wheel of each container meshing with the gear-wheel of the next adjacent container, means for locking each gear-wheel to its nut and actuating mechanism adapted to revolve the gear-wheel of one of the containers whereby the remaining gear-wheels will be revolved in unison therewith, for the purpose set forth.

In testimony whereof I hereunto affix my signature in the presence of two subscribing witnesses.

FREDERICK G. TEES.
